UNITED STATES PATENT OFFICE.

WILBUR J. WATSON, OF CLEVELAND, OHIO.

CENTERING FOR REINFORCED-CONCRETE BRIDGES, FLOORS, AND THE LIKE.

1,219,608.

Specification of Letters Patent. Patented Mar. 20, 1917.

Application filed September 8, 1913. Serial No. 788,498.

To all whom it may concern:

Be it known that I, WILBUR J. WATSON, a citizen of the United States, residing in Cleveland, in the county of Cuyahoga and

5 State of Ohio, have invented a new and useful Improvement in Centering for Reinforced-Concrete Bridges, Floors, and the like, of which the following is a specification.

10 My invention relates to reinforced concrete bridge construction, and one of its principal objects is a provision of parts supported by the reinforcements for molding the concrete into predetermined form and 15 position.

Heretofore, in practice, forms for the pouring of concrete around the reinforcement of bridges have been usually supported from the river bed which the bridge 20 spanned. It has often been found difficult to construct forms and support them in this manner, and such forms have often been disarranged or carried away by the current of the stream. I therefore provide forms 25 which can be suspended from cross bars extending across the upper surfaces of the metal reinforcement of the bridge and in such position as not to be interfered with during the setting of the concrete by the current of the 30 stream that the bridge spans. By thus hanging the parts directly from the steel frames which are suspended from the cross bars extending above the metal reinforcement, supports placed in the stream are dispensed with and the suspended forms may 35 be quickly removed after the setting of the concrete and used for other types of concrete construction. This reduces the cost of the forms and allows more rapid construction 40 of the bridge. I prefer to support the frames of the forms from cross bars supported above and by the reinforcing steel beams as this results in the greatest economy, both in construction and in the adjustment 45 of the position of the forms.

Further objects of the invention will appear hereinafter, the novel combinations and features of the invention being set forth in the appended claims.

50 Referring to the accompanying drawings, Figure 1 represents an isometric projection of a section of a broken-away portion of a bridge; Fig. 2 is a cross sectional view illustrating the reinforcing beams with the forms 55 supported thereon for properly molding the concrete, and Fig. 3 is a cross sectional view

of a preferred form of reinforcing beam including connecting bolts and pipe separators.

In order to illustrate the practical application of my invention I have shown in Fig. 1 an isometric projection of a portion of a bridge in connection with which my invention may be used, as shown in Fig. 2. While my invention may have a general application in the construction of buildings, etc., it is particularly adapted for the pouring of concrete about the metal reinforcement of a bridge because my improved centering forms can be suspended from cross bars extending across the top and supported by the I-beams 1 of the bridge which extend longitudinally between the end abutments located on the banks of the river. The side-walk portion 2 of the bridge is shown elevated 75 above the roadway 3. The I-beams are preferably constructed so as to increase the surface contact therewith of the concrete. In the present instance these I-beams are each constructed of longitudinal angle strips or 80 bars 4, 5 and 6, 7 connected together in pairs by means of bolts, as shown in Figs. 1 and 3. The longitudinal angle strips or bars 4, 5 are separated by means of pipe separators 8 located at intervals, and the longitudinal 85 angle bars 6, 7 are similarly separated by means of pipe separators 9. The upper and lower pairs of longitudinal angle bars are connected together by lattice work comprising strips or bars 10, 11 and 12. After the 90 I-beams have been properly placed on the end abutments the reinforcing cross bars 16, 17 are securely wired at 18 and 19 to the upper surfaces of the beams.

In Fig. 2 I have illustrated means for supporting the frames of the forms directly from the reinforcing beams. On top of the beams, on one flange of each, is located a short pipe 19'. Through this pipe extends a bolt 20 which also passes through one of the 100 flanges of the reinforcing beams and through the horizontal plate of the angle bar 21. This angle bar is thus rigidly secured to the upper portions of the beams and then occupies a horizontal position as shown in Fig. 2. 105 The angle bar 21 is composed of two parts 22 and 23 secured together at 24 by means of removable bolts. It will be seen that a plurality of holes 25 is provided in the end portions of the bars 22 and 23 so that the length 110 of the entire bar 21 may be adjusted to secure different positions of the vertical bar

26 which is rigidly connected at 27 to the bar 22.

The lower portion of the bar 26 is provided with a series of holes 28 so that the horizontal bar 29 may be secured thereto in different positions. The bar 29 is likewise provided with a series of holes for adjustment. At 30 a depending angle bar 31 is bolted to the inner end of the angle bar 29. The bar 31 is provided with a series of holes 32 for adjustably securing the horizontal angle bar 34 thereto at 35. The bar 34 is provided with a series of holes 36 so that the depending bar 31 may be secured in various adjusted positions. It will therefore be seen that by bolting the depending bar 26 at 27 to the horizontal uppermost bar 22 the bars 29, 31 and 34 may be suspended in adjusted position, the adjustments being permitted by the series of holes 28, 32, 33 and 36. Suspended from the upper horizontal angle bar 21 by means of the rods 37, 37 is a horizontal angle bar 38 which is adjustable in length as indicated by the series of holes 39. It will be understood that the bar 38 is composed of two parts 40 and 41 which are connected together at 42 by means of pins or bolts. If desired, the upper ends of the suspended rods 37 may be provided with permanent heads 43 or with nuts on screw-threaded upper ends of the said rods. In a similar manner the lower ends of the rods 37 may be screw-threaded and provided with nuts 44. By means of the nuts 43 and 44 the elevation of the horizontal bar 38 may be adjusted.

To the outer ends of the bar 38 are connected at 45 the depending bars 46, which are connected at one of the holes 47 to a horizontal bar 48 which comprises two parts 34 and 49 adjustably secured together at 50. It will therefore be seen that the depending bars 46 are secured at 51 to the horizontal bar 48. By means of the series of holes 47 in the depending bars 46 the horizontal bar 48 may be elevated or lowered, as desired.

The right-hand portion of Fig. 2 shows the flexibility of the form frames because the same size of bars are there used although adjusted to smaller inverted U-shaped frames. The upper horizontal angle bar 52, comprising the parts 53 and 54, is adjustably secured together at two or more of the holes 55 and supported by means of the bolt 20 and short pipe 19 on one of the flanges of a beam under the surface of the roadway of the bridge. By means of the rods 37 the horizontal adjustable bars 56, 57 are supported, as shown. At the outer ends of the bars 56 and 57 are connected at 58 and 59 the depending bars 60 and 61. The horizontal bar 49 may be connected at 62 to one of the series of holes in the left-hand depending bar 60. A horizontal adjustable bar

63 may be connected at 64 to the depending bars 46 and at 65 to the depending bars 60. The bar 63 may also be adjustably secured at 66, 66 to the depending bars 61, 61. The horizontal bar 63 may comprise a plurality of parts which are adjustably connected to each other by means of pins or bolts through a series of holes 67 and 68.

It will be understood that a set of such forms as illustrated in Fig. 2 may be connected to the metal reinforcement of the bridge at various points throughout its length. In short bridges two such sets would suffice, each set being located in a suitable position a distance from each end of the bridge. For bridges of long spans there may be several of such sets of forms connected to the reinforcing construction entirely across the bridge and located at various positions between the ends of the bridge.

Between the several sets of forms is placed timber sheeting to form the mold for the concrete. The horizontal boards 69 and 70 will rest on the horizontal bars 34 and 49 respectively, the boards 69 being located between the depending angle bars 31 and 46, and the boards 70 being located between the other depending angle bar 46 and the angle bar 60. The boards 69 extend longitudinally between the ends of the bridge directly under the beams constituting part of the reinforcement. The boards 71, 71 are similarly located in the frames which have been adjusted to smaller size and which are located underneath the roadway instead of under the sidewalk. The vertical portions of the timber sheeting are shown in Fig. 2 at 72, 73, 74, 75, 76, 77 and 78. The boards constituting this part of the concrete mold rest against the depending bars of the form frames and are located on opposite sides of the I-beams of the reinforcing structure. The upper portions of the timber sheeting of the concrete mold are located at 79, 80, 81 and 82. The boards constituting this sheeting extend longitudinally of the bridge between and at the sides of the I-beams and are supported mainly by the upper portions of the horizontal bars 29, 38, 56 and 57 of the inverted U-shaped frames which are located at various points along the bridge reinforcement. A board 83 may also be supported in the position shown and confined by the vertical bars 26. In order to form a curb for the sidewalk a board 84 may be suspended by means of bolts 85 from the bars 21 or be otherwise held in the position shown in Fig. 2.

When pouring the concrete into the timber sheeting supported by the centering forms, as shown in Fig. 2, I prefer to place a stop board 86 about half way between two beams so that only two beams will be covered at one pouring of the concrete. If desired, only one beam may be covered by a single

pouring which could be done by placing another stop board above the middle of the next form. As before explained, the steel members or beams are so constructed that 5 the concrete will not separate from the metal. This is because the flange angles of the beams are spread sufficiently to allow the concrete to flow between them and because the adhesive surface of the beam is materially 10 increased. It will be seen that by the use of the stop board 86 one or more of the beams may be covered or embedded in the concrete, and after the concrete has set sufficiently hard to carry its own weight between 15 the beams the forms may be removed and connected up at another portion of the structure for additional pouring of concrete. It would therefore be unnecessary to have a sufficient number of forms so as to enable 20 all of the concrete for the entire bridge to be poured at one time or continuously.

After the concrete has been poured about the beams of the sidewalk, as shown in Fig. 2, by the use of the stop board 86 and the 25 remainder of the structure shown, and it is desired to remove the forms to another portion of the bridge it may be taken apart, provided the concrete has set sufficiently to carry its own weight between the beams. By 30 removing the pins or bolts at 35, 50, 51 and 62 the horizontal bar 48 may be disconnected and also the timber sheeting 69 and 70. The depending bar 26 can be removed from the bar 22 by disconnecting at 27, or from the 35 bar 29 by disconnecting at 87. The bars 29 and 31 may be disconnected at 30, if desired. The bars 46 may be left connected at 45 or disconnected at such points from the bars 40 and 41. Before the latter can be re- 40 moved, however, the nuts 44, 44 should be removed when the bolts 37, 37 can be pulled out through the concrete. After the various parts suspended from the bar 21 have been disconnected the bolts 20 may be loosened 45 and the pipe 19' pulled out of the concrete and the holes that are left can be filled up.

In a similar way after one or more of the beams of the roadway have been poured with concrete the adjustable forms may be easily 50 removed to other locations where the operation of molding the concrete may be repeated.

It should be noted that by having adjustable centers for the forms the latter may be 55 used repeatedly and be immediately available for a great variety of work. This system of centers possesses considerable rigidity and can be easily adjusted to give more perfect alinement to finished concrete structures than other types of forms. The frames of the forms may be constructed of timber but I prefer to have them made of steel angle bars. Steel sheeting may be used instead of timber but the greatest economy is 60 effected by the use of timber sheeting. The

steel frames are preferable because the greatest economy results from their use as compared with timber frames.

When the bolts 20 are removed the nuts at the lower surface of the flanges of the 70 beams are left in the concrete. The top pieces 22, 23, 53 and 54 are preferably made in short lengths or in such lengths as to extend over two molding frames. A number of these top pieces may be bolted together 75 for greater strength, if desired, holes being provided in the separate lengths for that purpose. In the particular type of bridge illustrated the structural steel reinforcement is computed to carry the dead load without 80 assistance from the concrete, the concrete and steel structure and reinforcing bars acting together to resist the live load stresses. The structure cannot fail, therefore, by reason of faulty concrete and defective concrete 85 can easily be repaired. The structure, therefore, combines all the advantages of structural steel and reinforced concrete construction. Although the means of centering the 90 forms and suspending them is particularly adapted to the construction of bridges where it is undesirable to place the forms in a stream, the invention may have a general application. Furthermore, because of the flexibility of the forms they may be removed 95 in a short space of time and therefore rapid construction of the bridge may be effected. It will also be observed that the forms are very simple in construction and method of 100 application. These advantages can be obtained in the building of various kinds of reinforced concrete bridges even though the current in the stream is not considerable but where its depth is comparatively great.

While the drawings show form supports 105 made of steel angles, the same may be made of timber, or a combination of timber and steel or iron. In pouring concrete, the fluid is preferably poured into the forms from each end of the I-beams toward the center, 110 simultaneously.

Obviously those skilled in the art may make various changes in the details and arrangement of parts as defined by the claims without departing from the spirit and scope 115 of the invention, and I wish therefore not to be restricted to the precise construction herein disclosed.

What I claim and desire to have secured by Letters Patent of the United States is: 120

1. In combination, means adapted to co-operate with reinforcement for a reinforced concrete structure comprising longitudinal I-beams, consisting of a plurality of cross-bars supported by said I-beams, a vertical 125 curb strip suspended from said cross-bars, and a mold for pouring concrete mixture about the reinforcement suspended from said cross-bars.

2. In combination, means adapted to co- 130

operate with reinforcement for a reinforced concrete structure consisting of a plurality of cross-bars supported by a part of said reinforcement, horizontal strips adjustable in length and suspended from said cross-bars, additional strips connected to the outer ends of said horizontal strips and depending from the same, additional horizontal strips adjustably connected to said depending strips either horizontally or vertically, means for adjusting the length of said additional horizontal strips, and sheeting supported by both sets of horizontal strips and by the depending strips to form a mold for the pouring of concrete mixture about said reinforcement.

3. In combination, means adapted to cooperate with reinforcement for a reinforced concrete structure consisting of a plurality of cross-bars angular in cross section and adjustable in length, bolts for connecting the cross-bars to a part of said reinforcement, pipe separators for holding the cross-bars at a predetermined distance above the

reinforcement, suspension bolts connected 25 to said cross-bars, horizontal strips supported by said suspension bolts, means for adjusting the length of said horizontal strips, depending strips connected to the outer ends of said horizontal strips, additional horizontal strips, means for adjustably connecting said additional horizontal strips to said depending strips both as to vertical position and as to horizontal position, means for adjusting the length of said 30 additional horizontal strips, and sheeting resting on the upper and lower horizontal strips and against the depending strips to form a molding for the pouring of concrete mixture about the reinforcement. 35

In testimony whereof I have signed my name to this specification, in the presence of two subscribing witnesses, on this 2nd day of September, A. D. 1913.

WILBUR J. WATSON.
